LOCOMOTIVE VALVE

Pasquale Pascale, New York, N. Y., assignor to
 Dri-Steam Valve Corporation, New York, N. Y.,
 a corporation of Delaware

Application February 20, 1931, Serial No. 517,345

2 Claims. (Cl. 277—37)

This invention relates to improvements in locomotive valves, and has special reference to a steam drying balanced throttle valve of the type shown and described in my co-pending application Serial Number 498,441 filed November 26, 1930.

The valve about to be described is similar in the main to the valve described and illustrated in the pending application just mentioned. However, in the present instance, the balancing characteristics of the valve are augmented and improved in that with the construction hereinafter described, the possibility of perfect balance, or such balance as is predetermined upon, is obtained under all conditions likely to arise in the operation of valves of this character. More specifically stated, the object of the invention is to provide the valve proper with means cooperating with, or which may cooperate with the main balancing means, to insure, automatically the establishment of equilibrium of the main valve, and still more specifically stated, the invention comprehends the provision of an adequate number of check valves arranged in the head of the main valve, so that if the pressure exerted underneath the head of the main valve is greater than the pressure on the top of the head, or vice versa, the check valves will be automatically opened by such excessive pressure to establish the equilibrium mentioned.

In the drawing illustrating the invention—
 Figure 1 is a vertical diametrical section through the valve.

Figure 2 is a plan view of the valve with the upper structure thereof sufficiently broken away to show the arrangement of the check valves in the valve head around the central pilot valve in the head of the main valve.

Since the invention about to be described resides in the addition of the check valves, in combination with the valve as illustrated in the co-pending application hereinbefore mentioned, it is not deemed necessary to show the means for operating the pilot and main valves which are operated as usual, in that in the construction about to be described herein, and that shown in the pending application, the pilot valve is first operated to balance the main valve, and to thereafter operate it to desired opening and closing positions relative to the valve seat of the main valve.

Referring to the drawing, the numeral 1 designates a standpipe having its upper end bored out for the reception of the main valve 2 mounted for vertical sliding movement in the upper portion of the standpipe or within the chamber 3 formed between the head 4 of the said main valve, and a

head 5, bolted to the top of the standpipe 1 by bolts 6.

The standpipe is provided with an annular flange 6' at its top to which the upper end of a turbine casing 7 is bolted by means of bolts 8. The standpipe is further provided with a more extensive annular flange 9 below the flange 6, to which is bolted, by bolts 10, the lower end of the turbine casing 7. Still another flange 10' is provided on the standpipe to which is bolted, by bolts 11, the steam drying sleeve 12, provided with numerous small perforations or nozzles 13, just like those provided in similar sleeves or cylinders which form characteristic portions of the valve illustrated in the pending application, as well as those valves which are illustrated in patents already issued to me. The lower end of this sleeve is seated upon a narrow annular shoulder 14, provided upon the standpipe just above the larger annular flange 9. The standpipe in that portion thereof, opposite the perforated sleeve, is provided with a number of ports 15, through which the steam enters the dry-pipe after passing through the turbine casing and through the perforated cylinder or sleeve.

The main valve 2 comprises in the main, the head 4, and skirt 16, the lower edge of the skirt being beveled as indicated at 17 and adapted to seat upon a similarly shaped valve seat 18 formed at the lower inner edge of the ports 15 and just within the same. The valve is formed with a central boss 19, in which is threaded a pilot valve cage 19' chambered out in its lower portion to form a chamber 20, of a little larger diameter than the cylindrical opening 21 that is in the upper part of said cage. In the lower part of the cage is provided a series of ribs 22 for a purpose that will presently be described. The numeral 23 designates the valve stem whose upper end passes through a bushing 24 in a boss 25, centrally located in the head 5 of the standpipe. Between the bushing 24 and the stem of the valve is a bleeder 26, of sufficient size or capacity to form a proper size conduit for the steam to pass freely into the chamber between the head of the standpipe and the head of the main valve. The head of this stem is bifurcated as indicated at 27, for the reception of cross bar 28 secured to the stem by a pin 29, a connection which is usual and leads to the linkage by means of which the main valve and pilot valve are operated.

The upper part of the bushing 19 is provided with a valve seat 30 upon which seats the pilot valve 31 integral with the valve stem 23. Below

the pilot valve the stem is reduced in diameter as indicated at 32, thus forming a passageway between the lower portion of the valve cage and the chamber between the valve head and the standpipe head. Below this reduced portion 32, the stem is slightly enlarged as indicated at 33, which enlarged portion slides vertically between the ribs 22 which form guides for said enlarged portion. In the lower end of the valve stem is secured by a threaded shank, a lifting spider 34, adjusted with regard to the lower end of said stem and the lower ends of the central boss of the valve head, to limit the upward movement of the stem in the initial movement of said stem, 10 in opening the pilot valve preliminary to lifting the main valve, to open the ports 15 in the standpipe.

The main valve is provided with annular grooves 35, 35' in which are seated metallic rings 20 36, the expandible characteristics of which insure a steamtight fit between the inner periphery of the standpipe and the main valve.

The turbine casing 7 is provided with numerous vanes 37, suitably spaced apart to form 25 numerous elongated slots 38 through which the steam first passes in entering the turbine casing. Within the casing and spaced therefrom is an imperforate sleeve 39 extending entirely around the valve, the idea being that the steam in entering the slots between the vanes under great 30 pressure, is projected first against this sleeve or baffle and the condensates or moisture from the steam accumulating on the outside of the baffle, drops through the opening 40 and passes into 35 the upper ends of an adequate number of drainage pipes 41, which are provided for the passage of the condensate or "separate". After the steam passes into the space between the outer shell of the turbine casing and the baffle plate or sleeve 40 39, it passes into the conduit 42, between said baffle plate and the perforated sleeve or steam drier that guards the ports in the standpipe.

All of the foregoing description is for the purpose of enabling those familiar with the art to 45 comprehend the structure when described, disassociated from any other of my patents, or from the structures disclosed in the said copending application.

Now the following relates to the new structure, 50 not involved in any of those mentioned or referred to. In modifying my former structures, the valve head is provided with an annular depression 43 in which are arranged an adequate number of internally threaded circular openings 55 44, for the reception of seat rings 45, provided at their upper ends with valve seats 46, shaped to conform to the underneath periphery 47 of a corresponding number of check valves 48, formed with stems 49 guided in central sleeves 50, supported by short arms 51 integral with the sleeves and with the interior portion of the seat rings. The lower ends of the check valve stems are provided with nuts 52, adjustable on the stems to limit the upward opening movement of the 60 65 check valves by reason of their contact with the lower ends of the sleeves as the exigencies of the case may require.

In a manner differing from the construction shown in my co-pending application Serial Number 70 498,441 hereinbefore referred to, the central boss 19 is made integral with the skirt of the main valve by the provision of a number of ribs 53, that are provided between the threaded apertures for the check valves, thus providing a sort 75 of a table for said valves, the ribs, in a sense,

constituting legs by which the table and the central boss, is supported.

Doubtless, the operation of the valve described has become apparent to those skilled in this art, but nevertheless a brief description of the operation will now be made, more particularly for the purpose of accentuating the fact that the check valves in the main valve are provided for the purpose of keeping the valve balanced at all times, either in the opening or closing of the 80 85 same.

The head 5 of the standpipe, as we have seen, is provided with a bleeder of adequate capacity, open to the steam at all times. When the valve stem 23 is raised, the pilot valve 31 will be opened 90 to permit steam to pass into the lower part of the standpipe, thus relieving the pressure on the valve and bringing about the required balance desired to facilitate opening of the same, the pilot valve in the meantime, cooperating 95 with the peculiar construction of the main valve with relation to varying diameters of the main valve and piston rings as described in my application referred to at the outset.

Upon the initial downward movement, the pilot 100 valve is seated while there is pressure below the valve head. The pressure causes the check valves 48 to be automatically and simultaneously lifted from their seats, relieving the pressure from below the valve and establishing the desired equilibrium.

In the opening of the main valve, pressure 105 below the same will rapidly build up and become greater than the pressure on the top of the valve. The check valves therefore form means for 110 transferring said excess from below the valve to the top thereof, the valves being operated by such excess pressure to establish equilibrium of pressure on both sides of the valve. Similarly, in closing the valve, if pressure below the same is 115 greater than the pressure on the top of the valve, such excess pressure is relieved and transferred from below the valve to the chamber above the same, thus balancing the valve and facilitating the closing movement.

The valve described is of the type wherein the steam is dried or the moisture taken therefrom and returned to the boiler, and this drying is effected by reason of the fact that the steam passes through the slots between the vanes of 125 the turbine casing 7, where it comes in contact with the imperforate sleeve 39 against the outer surface of which the moisture of which the steam is denuded, accumulates on said plate and goes back into the boiler through a number of drain 130 pipes 41. The steam then partially dried, passes upward and then downward into the conduit 42 and against the outer face of the perforated sleeve or steam drier 12, where it is further dried before passing through the ports in the 135 standpipe, the moisture of which the steam is denuded at this point, passing back into the boiler, also through the drain pipes 41.

It will be noted that the check valves 48 are arranged radially around the valve stem and 140 equi-distant apart, thus uniformly distributing the pressure over the top and bottom of the main valve as the case may be, in the opening and closing movement of the valve, thus insuring a true vertical movement of the valve, or preventing a 145 sort of a tortional displacement in its operation.

What I claim is:

1. In a locomotive valve, the combination of a standpipe having a cover for the top having an opening in constant communication with a fluid 150

source under pressure, ports in said standpipe below the cover and having valve seats at their lower ends, a main valve slidably mounted with relation to said seats, a pilot valve in the main valve extending through the closure of the top of the standpipe and having operative connections extending outside of the standpipe, whereby both the pilot valve and main valve are operated, a check valve carried by the main valve and above the ports in the standpipe and normally subject to a constant pressure through the opening in the cover of the standpipe and adapted to be opened when the pressure below the main valve exceeds that above said valve for the purpose of establishing equilibrium between the pressures that occur in the operation of the valve in both opening and closing and on both sides of said main valve.

2. In a locomotive valve, the combination of a standpipe having a cover for the top having an opening in constant communication with a fluid source under pressure, ports in said standpipe below the cover and having valve seats at their lower ends, a main valve slidably mounted with relation to said seats, a pilot valve in the main valve and extending through the closure of the top of the standpipe, and having operative connections extending outside of the standpipe, whereby both the pilot valve and the main valve are operated, a plurality of check valves carried by the main valve and adapted to be opened when the pressure below the main valve exceeds that above said valve for the purpose of establishing equilibrium between the pressures that occur in the operation of the valve in both opening and closing and on both sides of, said main valve, said check valves being radially arranged around the stem of the main valve and spaced equi-distant apart, whereby the pressure exerted upon the main valve is distributed uniformly on the surface of said valve.
